WILLIAM C. RATH, OF NEW YORK, N. Y.

PROCESS FOR RECLAMING LUBRICATING OIL

Refile of abandoned application Serial No. 635,576, filed April 30, 1923. This application filed March 20, 1929. Serial No. 348,676.

My invention relates to a process of reclaiming used lubricating oil, and especially spent oil from internal combustion engines, such as automotive engines, and for producing gas in which the lower boiling point components of the used oil are introduced as enriching ingredients.

In the operation of internal combustion engines, and especially engines of the automotive type, the lubricating oil becomes contaminated with lighter hydrocarbons, that is, oils generally designated as gasoline or kerosene, which are parts of the engine fuel that pass the pistons and piston rings and go into the crank case where they mingle with the lubricating oil and dilute it and lower its lubricating value so that in a greater or less time, depending on various conditions, it is unfit for use.

The oil is also gradually contaminated by particles of carbon, this term being used to include actual carbon and various gritty and other materials drawn into the engine with its air supply, and metal particles. It is customary to draw off the crank case oil at intervals so that fresh, clean oil may be supplied to the engine. In this way dirty or spent lubricating oil accumulates in garages and service stations, and while in some cases the oil has been filtered to remove the carbon, metal particles and other solids, no satisfactory plan has been devised, within my knowledge, for removing, on a practical or commercial scale, the lighter components from this spent oil, to render it fit for reuse as an engine lubricant. The result is that this spent oil is usually thrown away, being frequently dumped into sewers with various obnoxious results, including gas explosions, contamination of streams, and other conditions unnecessary to mention.

One important object of my invention is to recover in some useful form, waste oils such as crank case oil, including the lighter fractions, even those so volatile as to be difficult to condense. Another important object is to make this spent oil available for reuse as an engine lubricant on a practical or commercial scale, by treating it in connection with the production of a merchantable gas in such a

way that the lighter components are removed from the lubricating oil, and added to the gas as enriching components, leaving the lubricating oil after the usual filtrations or settling to remove grit, or the like, in substantially its original condition, and available for sale or reuse as a lubricant or for further treatment if desired; for instance, if it is desired to grade it into lighter and heavier lubricants it may be treated by fractional distillation for this purpose. Other objects of my invention will be apparent hereafter.

The process consists in one suitable form, briefly described, in producing any suitable low grade gas in a suitable gas producing apparatus, for instance, ordinary coal gas, producer gas, or water gas, and supplying this gas while hot to a suitable oil "separator" or oil-gas generator into which the spent or waste lubricating oil is supplied in a suitable way at a proper rate.

The hot gas vaporizes, entrains and carries off from the spent lubricant its lighter components, and the process may be regulated so that substantially all of the gasoline and kerosene components, and only these, are removed and added to the low grade gas as enriching components; or the process may be regulated so that a greater or less range of hydrocarbons is removed from the lubricating oil; for instance, if a larger amount of hydrocarbon is desired for enriching material, or if it is desired to produce a heavier grade of lubricant in the reclaimed product, the intensity of the process may be increased and some of the oil of the lighter lubricating ranges may be evaporated and carried off with the gas. The spent oil may be filtered to remove its extraneous solids before or after it is subjected to action of the gas from the gas producer, or both, depending on the character of the impurities and whether or not their separation is promoted by previous heat treatment.

The process may be considered either from the standpoint of gas production, in which the object is to provide enriching material for low grade gas from a source hitherto unavailable, either with or without producing a greater or less quantity of a valuable by-product, namely, lubricating oil; or it may

be considered from the viewpoint of reclaiming or making valuable spent lubricating oils contaminated by unfilterable impurities, such as diluents of the gasoline or kerosene grades, which have heretofore been waste products, with greater or less incidental production of a valuable by-product; namely, the lighter diluent components thereof which are added to low grade gas to enrich the same and increase its merchantable value.

The characteristics and advantages of the invention are further sufficiently explained in connection with the following detail description of the accompanying drawings which show certain representative physical embodiments of an apparatus for carrying out the process, and sufficiently explain representative performances of the process; and after considering these, persons skilled in the art will understand that many variations may be made within the principles of the invention, and I do not limit myself to details except as claimed hereafter.

Figure 1 is a schematic view or flow diagram, explaining the process in one form and also sufficiently illustrating diagrammatically one suitable apparatus embodying the invention.

Figure 2 is a vertical section of a suitable "separator" or reclaimer for waste motor oil.

In Figure 1, A designates any ordinary or suitable gas generator, such as a typical water gas generator. At B is indicated in dotted lines any suitable gas producer which may be used alternatively. In the broader aspect of the invention the gas generators or producers A or B represent any suitable source of gas supply; that is to say, any source from which a suitable volume of low grade gas may be supplied to be enriched by portions of spent motor oil or to be brought in contact with spent motor oil for the purpose of removing diluent components therefrom.

The hot gas, which is usually of a character which may be described as low grade gas, is conveyed from the gas generator or producer A or B through a suitable pipe 1 or 1^a to a device or apparatus C of any suitable type for treating waste motor oil. This pipe is broken off at 1^b to indicate that it may be of great length to secure air cooling, or that a cooler of any suitable design may be inserted at 1^b if a large proportion of lubricating oil is to be separated, or that it may be short and well insulated in case relatively large amounts of the hydrocarbons are to be removed; for example, if not only diluting gasoline and kerosene, but some of the lighter portions of the lubricating oil are to be removed and used as gas enriching agents.

One suitable form of separator or reclaimer for this purpose, which is preferable in some cases, is shown in Figure 2. This includes a casing or jacket 10 which may be of fire brick or concrete or other suitable heat insulating

material. Somewhat above the bottom of the casing is a grate 11 which supports a mass 12 of fragments of brick or other suitable oil and heat resisting material. Suitably supported in the top of the casing is a spray head or suitable arrangement of pipes 13 provided with perforations for the discharge of oil. An opening may be provided in the casing at 14 close to the grate to permit the casing to be cleaned out, and this opening is closed by cap 15.

The pipe 1 discharges the hot combustible gas below the grate and usually a shield 16 is placed over the end of the pipe to prevent the dripping of oil into the pipe.

Referring to Figure 1, the dirty or waste motor oil is supplied from a storage tank D in any suitable way, suitable pumps or gravity feed arrangements being provided in the apparatus as may be necessary or desirable, to the oil distributing or spray head 13 in the separator. Desirably a filter E may be interposed between the storage tank and the separator to free the oil from carbon and other solids. In this case, the oil goes from the storage tank through pipe 2 to the filter, and from the filter through pipe 3 to the header 13. The oil discharged in fine streams or drops from the perforations in the oil distributing pipes 13 falls on the checkerwork 95 provided by the broken fragments 12 and spreads over the surfaces of these fragments as it descends, and in this way the oil is spread into a thin film over a very large surface and is brought in intimate contact with the ascending hot gas from pipe 1 which vaporizes the lower boiling point constituents of the waste oil; namely, the gasoline and kerosene components thereof, and these oil vapors are absorbed or entrained in the hot gas and pass with it from the separator through pipe 4 to any suitable cooler or condenser F.

When the oil in its descent through the checkerwork 12 reaches grate 11 it is practically or entirely freed from its lighter or diluent components and it then passes through the grate 11 to a sump provided in the lower part of chamber 10 from which it is conveyed through a pipe 7 to a storage tank M. After mechanical clarification as by filtering, settling or treatment in a super-centrifugal machine, the reclaimed oil is in practically its original condition, available as a lubricant for internal combustion engines, or for other purposes.

The separation or reclamation operation performed in this case in the chamber 10 may be easily regulated in various ways to produce different results. The amount of heat contained in the combustible gas supplied through pipe 1 may as suggested be regulated simply by changing the length of the pipe between the gas generator or producer A or B and the separator C, or by jacketing the 130

5 pipe to retain heat or by cooling the pipe in any suitable way to remove part of the heat from the gas. In some cases additional heat may be supplied to or in the separator, if additional heat is needed at this point. The following are sufficient examples of various 10 reasons for any ways in which the amount of heat or the intensity of the separation operation may be varied or controlled. Waste motor oil may be collected from various 15 sources and will usually consist of various grades of oil, that is, lubricating oils which are originally of the lighter, heavier, or intermediate grades.

15 The spent oil in storage tank M will therefore usually be a mixture of intermediate grade and by the ordinary treatment in the separator C as above described, in accordance with which only the diluent gasoline and kerosene components are removed, the 20 resulting reclaimed product will be an oil of intermediate grade or viscosity. If it is desired to produce in the performance of my process a heavier grade of oil, the intensity 25 of the separation treatment in separator C may be increased by increasing the heat of the gas supplied through pipe 1 in any of the ways above explained, or by providing additional heat if that is necessary, resulting 30 in driving off not only the lower boiling point diluents but a certain portion of the lighter lubricating component of the oil.

35 Otherwise, the reclaimed oil of whatever grade it may be as it reaches storage tank M, may be treated by fractional distillation to produce any desired grades of lubricant within the ranges included in the reclaimed material.

40 The gas discharged from the separator C through pipe 4 is therefore the ordinary or low grade gas, enriched by the addition of mineral oils derived from the spent lubricant, and therefore of a high grade and valuable, for heating or illumination, or other purposes.

45 If the temperature is sufficiently high to permanently vaporize the diluent materials a certain part of the lubricating component may be temporarily vaporized without dissociation and may be physically entrained with the gas. The gases discharged from the separator C may therefore be conveyed through a pipe 4 to a condenser of any known or suitable type for the separation of any condensable part of the gases, and in certain 50 of the instances above given some hydrocarbon in the lower boiling point lubricating range and also in some cases some of the still lighter or kerosene range of the original material may be separated from the gases in the 55 condenser. The condensate of whatever character is conveyed to a storage tank H, and desirably a gas trap or seal pot G is interposed in the pipe line 6, 7. The condensate in tank H may therefore consist of some of 60 the lighter lubricating oil fractions, together

with, in some cases, some part of the kerosene range of the original spent oil.

When desired, two or more condensers in series, maintained at differentially lower temperatures may be used, and these temperatures may be adjusted to separate out the two or more fractions of condensate, instead of resorting to fractional distillation of the entire distillate when condensed.

When the condensate is contaminated by any of the kerosene it may be treated by fractional distillation in any suitable way, or it may be returned to the separator C for further treatment in the normal operation of the separator as above explained. When the 75 temperature conditions in the separator are such that all of the lighter components, that is to say, the kerosene and gasoline are vaporized, none of these materials will be separated out in the condenser F and the condensate going to tank H will be only some part of the lighter fractions of the lubricating oil. This may be disposed of in any desired way as reclaimed lubricating oil, or 80 may be used to mix with a part of the reclaimed oil in tank M to modify the grade 85 thereof.

80 The enriched gas is conveyed from the seal pot G through a pipe 8 to any ordinary or suitable gas scrubber J, and then to a storage 90 tank K for any desired utilization.

95 When desired the filter L may be inserted in the pipe line 9 leading from the separator to storage tank M. Especially this filter may be so arranged if a filter E is not provided 100 between the storage tank D and the separator.

105 The present application is a refiled application of my abandoned application Serial No. 635,576, filed April 30th, 1923.

What is claimed as new is:—

110 1. The herein described process of purifying and reclaiming spent lubricating oil by distillation with a combustible gas, comprising subjecting the spent lubricating oil to the action of warm combustible gas from a gas generator whereby diluent components of the oil are vaporized and carried away, and the lubricant is reconditioned for further use.

115 2. The herein described process of purifying and reclaiming spent lubricating oil by distillation with a combustible gas, comprising supplying combustible gas at regulated temperatures in intimate contact with the contaminated oil whereby regulable percentages of the oil are entrained and carried off 120 with the gas, and the oil is freed from the lighter diluents.

125 Signed at New York in the county of New York and State of New York this 7th day of March, A. D. 1929.
